UNITED STATES PATENT OFFICE.

CHARLES A. ENSIGN, OF NAUGATUCK, CONNECTICUT, ASSIGNOR TO THE
GOODYEAR METALLIC RUBBER SHOE COMPANY, OF SAME PLACE.

DESIGN FOR OVERSHOES.

SPECIFICATION forming part of Design No. 11,638, dated February 3, 1880.

Application filed January 7, 1880. Term of patent 3½ years.

To all whom it may concern:

Be it known that I, CHARLES A. ENSIGN, of Naugatuck, in the county of New Haven and State of Connecticut, have invented a new
5 Design for Overshoes; and I do hereby declare the following, when taken in connection with the accompanying drawing and the letters of reference marked thereon, to be a full, clear, and exact description of the same, and which
10 said drawing constitutes part of this specification, and represents a perspective view.

This invention relates to a design for the ornamentation of overshoes; and it consists in the ornamentation, as shown in the accompanying
15 illustration.

The general outline of the shoe is common and well known. Across the instep are several lines, each composed of a series of raised points. On these lines, down the center, is

the representation of two parallel rows of perforations connected by diagonal lines crossing each other, giving to that part of the shoe the appearance of being laced. An ornamental raised bead commences in a scroll form at the toe, thence running backward, and terminating in a divided scroll on the side of the counter and a like bead on the opposite side of the shoe, all as shown in the accompanying illustration.

I claim—

20 The design for the ornamentation of overshoes, as described, and shown in the accompanying illustration.
